J. S. TIMMONS

TELEPHONE RECEIVER

Filed May 19, 1922

Inventor-
John S. Timmons.
by his Attorneys-
Fowson & Fowson

UNITED STATES PATENT OFFICE.

JOHN S. TIMMONS, OF PHILADELPHIA, PENNSYLVANIA, ASSIGNOR TO PENN HEAD SET COMPANY INCORPORATED, OF PHILADELPHIA, PENNSYLVANIA, A CORPORATION OF PENNSYLVANIA.

TELEPHONE RECEIVER.

Application filed May 19, 1922. Serial No. 562,106.

To all whom it may concern:

Be it known that I, JOHN S. TIMMONS, a citizen of the United States, residing in Philadelphia, Pennsylvania, have invented 5 Telephone Receivers, of which the following is a specification.

One object of this invention is to provide a compact, simple and rugged telephone receiver particularly designed for use 10 as part of a head set, which shall be of such construction that its various parts are rigidly clamped in place so as to be effectively prevented from such vibration as might interfere with the desired operation or functioning of the instrument.

It is further desired to provide a telephone receiver of the above type in which there shall be no exposed terminals and whose conductors shall be contained within 20 a cord branched inside rather than outside of the receiver case, and in which said cord is immovably clamped so as to avoid the necessity for tie cords and preventing the likelihood of abrasion of the cord or cable 25 insulation.

I further desire to provide a telephone receiver having novel means for clamping its conductor cable in the casing to prevent stress on the terminals and avoidable chafing of the cable itself, together with novel 30 means for connecting the conductor wires to the magnet and windings.

These objects and other advantageous ends I attain as hereinafter set forth, reference being had to the accompanying drawings, in which,

Fig. 1 is a side elevation of a telephone receiver constructed in accordance with my invention;

Fig. 2 is a front elevation of the receiver casing with the front member thereof removed to show the detail arrangement and construction of the interior parts of the receiver;

Fig. 3 is a transverse vertical section on the line 3—3, Fig. 2; and

Fig. 4 is a fragmentary vertical section of a detail of my invention.

In the above drawings, 1 represents a flat cylindrical metallic case closed on one face and having its free edge externally threaded 50 for the reception of the face or cover member 2, which is centrally perforated. Mounted within the casing and substantially con-

centric therewith is a magnet 3 of the horse shoe type having mounted between each of its ends and the adjacent inner face of the back of the casing one arm of an L-shaped pole piece 4.

In each case a bolt 5 passes through the rear wall of the casing, through the pole piece and through the end of the horse shoe magnet and has mounted upon its inner end a nut 6 which serves to rigidly hold to the end of the magnet one end of a stiff metallic strip 7. The latter however is suitably insulated both from the bolt and from the magnet 3, so that said bolt serves merely as a device for rigidly holding it in place.

Each of the pole pieces 4 is extended at 70 right angles so as to provide two poles lying substantially parallel and within the space defined by the horse shoe magnet 3. On these poles are mounted the windings of a magnet 8—8, which are connected together and also respectively connected to the two strips 7—7. A suitable sheet metal or equivalent diaphragm 9 is clamped between the free edge or face of the casing 1 and the cover 2 so as to be held immediately adjacent but suitably spaced away from the adjacent pole pieces 4.

Each of the metallic strips 7 is offset downwardly and then forwardly adjacent the ends of the horse shoe magnet and each 85 of them has mounted in it a clamping screw 10 for the reception of a terminal of one of the conductors 11 leading into a flexible cable 12. These conductors do not leave the cable until it has passed into the casing 90 1 and for the purpose of immovably holding it in place therein so as to prevent tension being brought on the terminals or strips 7 with which they are associated, I provide a flanged bushing 13 mounted in 95 an opening in said casing and longitudinally slot this bushing so that it may be contracted by suitable means. For this purpose it is externally tapered and threaded for the reception of a suitable nut 14, which after 100 the cable 12 has been inserted, may be set up so as to rigidly clamp the bushing in the casing wall as well as to tightly clip the cable to the bushing whereby it is held from possibility of movement.

From the above description it will be appreciated that when properly assembled, all the parts of my device are rigidly mounted.

ed so that undesirable relative movement or vibration cannot occur. The parts themselves are simple and substantial in form, lending themselves to convenient and inexpensive manufacture and assembly. The construction is such that the receiver is efficient and thoroughly practical under operating conditions, the arrangement being such that likelihood of any of its parts getting out of adjustment or becoming inoperative is reduced to a minimum.

Moreover the bushing 13 and nut 14 cooperate to make a tight joint with the cable 12 and thus effectually exclude moisture from the interior of the instrument.

I claim:

1. The combination in a telephone receiver of a casing; a magnet in the casing; pole pieces for the magnet; windings on the pole pieces; bolts mounted on the back of the casing and holding the magnet and its pole pieces thereto; with terminal mem-

bers mounted on but insulated from said bolts and electrically connected to the windings on the pole pieces.

25

2. The combination in a telephone receiver of a casing; an electromagnet therein; bolts mounted in the back of the casing for holding said magnet in place; with two terminal strips respectively connected to the ends of the magnet winding and rigidly connected to but insulated from said bolts.

3. The combination in a telephone receiver of a casing; an electromagnet therein; bolts mounted in the back of the casing for holding said magnet in place; two terminal strips respectively connected to the ends of the magnet winding and rigidly connected to but insulated from said bolts; and a cable extending into the casing and branched inside of the same, the conductors of said cable being respectively connected to said terminal strips.

JOHN S. TIMMONS.
